CLAIM

The ornamental design for an acoustic environment module, as shown and described.

DESCRIPTION

FIG. 1 is a perspective view of my new design for an acoustic environment module;

FIG. 2 is a front elevation;

FIG. 3 is a rear elevation;

FIG. 4 is a side elevation;

FIG. 5 is a top plan; and,

FIG. 6 is a bottom plan.

FIG. 5

FIG. 6

FIG. 4
